UNITED STATES PATENT OFFICE.

EDWARD J. O'CONNELL, OF FORT WAYNE, INDIANA; ELWIN M. HULSE ADMINISTRATOR OF SAID EDWARD J. O'CONNELL, DECEASED.

DEWATERING ATTACHMENT FOR CONCENTRATING TABLES.

Application filed April 20, 1921. Serial No. 462,974.

To all whom it may concern:

Be it known that I, EDWARD J. O'CONNELL, a citizen of the United States of America, and resident of Fort Wayne, in the county of Allen and State of Indiana, have invented certain new and useful Improvements in Dewatering Attachments for Concentrating Tables, of which the following is a specification.

This invention relates to improvements in dewatering attachments for concentrating tables, and the object thereof is to provide a device adapted to be attached to and operated in conjunction with a reciprocating table, by means of which water used in washing coal on the table will be delivered from the concentrator separately from the coal; and another object is to provide means in conjunction with a concentrating table for the separation of the water, used in washing coal on the table, together with the very fine particles of coal from the coarser grades. Ordinarily, in coal washing operations in which concentrating tables are used, washed coal is discharged from the table together with a considerable quantity of water, which necessitates subsequent treatment in order that the coal may be relieved of the water so as to render it marketable. It is also very desirable that the very fine particles of coal, as well as the water, be eliminated from the coarser grades. As such operations are ordinarily carried out by additional machinery with attendant complication of operations, the present invention affords an advantage in that the coal is discharged from the washing apparatus in a state practically freed from moisture and the extreme fine particles. These objects are accomplished by the construction illustrated in the accompanying drawings in which:—

Fig. 1 is a plan view of a concentrating table and the invention applied thereto;

Fig. 2 is a side elevation projected from Fig. 1; and

Fig. 3 is an end elevation of the table and the attachment.

Similar characters of reference indicate corresponding parts throughout the several views and referring now to the same:

1 is a concentrating table deck of the usual type including a frame 2 upon which the deck proper is built, the surface of the deck having thereon a series of riffles 3. Also, a feed box 4 and dressing water distributing

launders 5 are arranged in the usual manner along the feed side 6 of the deck. The support for the deck and the mechanism for imparting longitudinal reciprocating movement thereto are not herein shown, as they may be of any suitable construction, and form no part of the present invention.

The deck herein shown as an example of the type to which the invention is applicable is operated as usual, coal and water being introduced into the feed box 4 from which it passes onto the deck, and dressing water being applied along the feed side of the deck from the launders 5, the deck being slanted transversely so that the coal and water gravitally pass across the table to the discharge side 7. The particles of slate, stone and other substances heavier than coal, that tend to lag upon the surface of the deck, become progressed in the usual manner to the concentrates discharge end 8 of the deck.

The present invention comprises the construction and arrangement of a dewatering device in conjunction with the deck at the discharge side thereof and by which the coal and water passing from the discharge side of the deck are conveyed therefrom and separately discharged.

The device is comprised of a launder 9 that is secured along one side thereof to a supporting beam 10 which is rigidly fixed to the frame 2 of the deck and extends from one end thereof to the other. Also, the launder 9 is supported along its opposite side by brackets 11 that are secured to the frame. The launder is positioned partially under the discharge side of the table and so as to have a downward slant toward the concentrates discharge end of the deck in order that material that passes into it from the side of the deck will tend to flow toward the open front end.

A feature of the invention consists of a screen 12 that forms part of the bottom of the launder 9 adjacent its open or discharge end, through which the water passes and becomes separated from the coal that passes over the screen and is discharged from the open end of the launder. The screen 12 is bent slightly at a point along the line— α , its rear portion having approximately the same declivity as the bottom 13 of the launder proper, and the portion adjacent the discharge end of the launder being more nearly level than the other portion.

In the operation of the invention the table is reciprocated longitudinally and operated in the usual manner, the coal and water passing across the riffled area on the table from 5 which it is discharged into the launder 9, and the heavy refuse or concentrates being moved forwardly by the impellent motion of the table to the discharge end 8. The dressing water applied to the table from the 10 distributing launders flows transversely across the table washing the coal from the heavier refuse during its passage to the launder 9. Movement is imparted to the launder 9 because of its rigid connection 15 with the table, and its action therefore tends to move the coal forwardly to the discharge end. As the coal passes down the launder over the screen, the water and the very fine particles of coal pass through the screen and 20 are thus separated from the coal that passes over the screen. The forward portion of the screen, being of less declivity than the bottom 13 of the launder 9, causes the coal

to lag somewhat in its passage over the screen, thus the separation of the water 25 from the coal is facilitated.

By positioning the launder 9 so as to extend partly under the side of the table the occupied space of the concentrating apparatus as a whole is materially conserved. 30

What I claim is:—

In combination with a concentrating table having longitudinal reciprocating movement, a launder in fixed relation with the table and movable longitudinally therewith 35 located under the tailings discharge side thereof, there being a screen forming the bottom of the discharge end portion of the launder, said screen extending in contiguous longitudinal planes, the innermost portion 40 of said screen extending in the general plane of the bottom of the launder and the other portion extending therefrom with less declivity than the former portion.

In testimony whereof I affix my signature.
EDWARD J. O'CONNELL.
